TENSION CONTROL MEANS

Arthur W. Broms, Chicago, Ill.

Application February 23, 1932, Serial No. 594,523

11 Claims. (Cl. 242—75)

This invention relates to tension control means, and more particularly to means for controlling the tension in sheet material unreeling from a roll.

5 The main object of this invention is to provide means which will always maintain an even or uniform tension in sheet material traveling from a roll; as for example, a continuous sheet of paper traveling from the paper-roll to a printing press.

Another object is to provide control means for sheet material drawn from a roll, so arranged that, whenever the pull on the material decreases or when the material breaks and the roll by its momentum continues to rotate and unreel, said control means will be automatically actuated to check the rotation of the roll and the unreeling of the sheet material in such a manner as to maintain an even tension in the material.

Still another object is to provide such tension control mechanism which is adapted to be adjusted or pre-set to produce a certain retarding effect for maintaining a desired tension in material that is unreeling and while the material is traveling at a substantially constant rate of speed, and which mechanism will automatically produce additional retarding effect when the material becomes slack or breaks and the roll continues to unreel ahead of the lead, such additional retarding effect being automatically diminished as such desired tension is again imparted to the unreeling material.

A further object is to provide an improved tension control means for unreeling material, preferably by equipping it with retarding means which engages the material and is driven through such engagement, and which also includes brake means to apply a braking effect upon said retarding means and therethrough to the material engaged thereby while it is being unreeled.

A still further object is to provide control means for retarding and maintaining an even and balanced tension in material drawn from a roll, wherein said retarding means includes flexible means which engages and travels along with the material and maintains the required arcing contact with the roll and furthermore includes resilient means for normally maintaining an equalized uniform tension in the material, whether the roll is a full new one or a small depleted one.

Still another object is to provide such improved tension control means which comprises weighted

and spring balanced retarding means for engaging and traveling along with the continuous sheet of material while it is being drawn from the roll, and which control means further includes brake means adapted to be pre-set for providing and maintaining a desirable slight tension and retarding effect under usual conditions, also including additional brake means which is automatically applied when the pull on the material is decreased or stopped and the roll continues to unreel too freely, and which automatic brake means is again released when the slackness in the material is taken up.

These and various other objects and advantages will become apparent from the following description, taken in connection with the accompanying drawings, in which the invention is illustrated in its preferred form of construction, it being understood that various other arrangements and forms of construction may be resorted to for carrying out the objects and purposes of this invention.

In the drawings:

Fig. 1 is a perspective view illustrating my novel tension control means in its preferred form of construction, and as operating on a continuous sheet of material while it is being drawn from the roll.

Fig. 2 is a side elevational view of the invention, showing in full lines the parts in the normal operative position, and showing in broken lines the position assumed by certain parts when the roll runs ahead of the lead.

Fig. 3 is an enlarged elevational view of the combined manual and automatic brake device.

In certain machines, such as printing presses, which perform work on sheet material which is drawn or supplied from a roll, mechanism is provided for supporting and journaling the roll, and this preferably comprises a swingable supporting frame containing a pair of side bars 8 connected centrally by a rod 9 which is adjustably mounted in bracket members or supporting posts 10, said bars and rod being normally clamped or held firmly in position within said bracket members, but to allow swinging and adjusting thereof, as by the use of means 11, so as to place and support the roll in the desired position. Each end of the pair of bars 8 is provided with suitable means, as indicated at 12, for centering and rotatably supporting the roll of paper between said ends.

The continuous sheet of paper or material 13 issues from the upper roll 14 mounted between the upper ends of said bars, while a new roll 15

is, in the meantime, mounted between the lower ends of said bars, to be swung and supported in the proper upper position by the manipulation of means 11, as soon as the preceding upper roll 5 is depleted, as is well understood in this art.

In my invention the continuous sheet of material 13 is guided from the roll 14 over a guide roller 16 which has stems 17 at its ends journaled in bearing blocks 18 which are adjustably mounted, as by means of adjusting elements 19, in a pair of bracket arms 20, said arms being swingably supported, for example, by bracket means 21 provided on upper frame means or a beam 22 which is supported on frame posts or standards 23. Two check members, such as dash-pots 24, are pivotally mounted by bracket means 25 on the upper frame means 22 and have protruding piston rods or stems 26 pivotally attached to lugs 20' on the sides of arms 20, so that when the lead from the feedroll becomes slack said arms 20 with roller 16 may descend freely through the action of gravity, from the slanting retracted position shown in full lines in the drawings, to the lower position shown in broken lines in Fig. 2; however, so that the return travel of said arms 20 and of the rods 26 into dash-pots 24 will be effected slowly and gradually as the tension in the sheet of material is again increased.

This improved tension control means includes 30 retarding means or members 30 which engage the sheet of material and travel a certain distance therewith, and whereby a slight retarding effect and tension is constantly applied to the traveling material. This means preferably comprises a plurality of endless traveling belts which are mounted on a set of pulleys 31 secured on a shaft 32 journaled in bearing portions 33 provided on bracket arms 34 supported on upper frame means 22 or in some similar manner. 35 These belts further travel over a second set of pulleys 35 mounted on a shaft 36 which is supported in bosses 37 provided on supports or uprights 23; also traveling around a third set of pulleys 38 which are supported in the looped 40 lower ends of the belts. Said belts engage the material 13 on roll 14 and are driven by such engagement to travel freely over the pulleys 31, 35 and 38; and as these belts are of flexible or pliable material, as for example, leather, they 45 will curve or arc properly on the roll whatever the size of the roll may be, whether a small depleted roll, as shown by roll 14 in Fig. 1, or a large new roll as shown by roll 15 therein.

Means is provided to constantly produce a 50 moderate tension in the belts and maintain a moderate pressure of the belts on the material roll, to normally maintain a slight retarding effect on and tension in the unreeling material. For this purpose, the lower pulleys 38 are weighted, each pulley having a pair of rods 39 depending from its axle shaft and carrying a weight 40 at the lower ends thereof, being also adapted to receive and support additional weights 41 thereon, as may be necessary. Said weights 40 and 41 travel vertically along guide rods 42 which are retained in proper position by a cross-bar 43 mounted on uprights 23. The variation in the size of the roll is automatically compensated for by the weighted pulleys 38 through their upward and downward movement along the guide rods 42.

I also provide resilient means for equalizing the tension on the material to compensate for the difference in diameter or the size of the roll, and for that purpose springs 44 are preferably mount-

ed on guide rods 42, between the weights and cross-bar 43. When the upper roll is full, and its diameter and momentum is at a maximum, the belts lift the weights and greatly depress the springs, thereby increasing their tension; and as the roll decreases in size, the belts allow the weights to descend and the springs to become slack and decrease their effect, thereby decreasing the tension in and retarding the effect of the belts upon the roll of material.

A slight and uniform retarding effect upon the unreeling material is thus automatically maintained through these belts and this primary retarding means, due to the weighted and spring-equalized pulleys 38 and the friction caused by the pulleys 31 and 35 with their shafts 32 and 36. This retarding effect can be further increased by adjusting side bars 8 and swinging the active upper roll 14 downwardly, and thereby producing a greater arcing contact between said roll and the belts, thus causing a longer grasp of the belts on the material and also a greater tension in the belts and greater retarding effect thereby on the material. This retarding means is pre-set, by using the proper weights 40 and 41, and springs 44 of proper tension, and by properly adjusting bars 8 and roll 14, thereby pre-arranging this means for the desired slight and equalized retarding effect and tension on the material.

I furthermore provide means herein for producing additional retarding effect and tension in the material as it is being drawn from the roll; and this means is preferably in the form of brake means applied to the above described primary retarding means or control means, and like it, is adapted to be pre-set, so as to increase the retarding effect on the roll and the tension in the material drawn therefrom, whenever found expedient. This brake means or additional retarding means preferably comprises a brake drum 50 secured on one end of shaft 32, and cooperating brake means, for example, a brake band 51 carrying brake shoes 52 to engage the exterior of said drum, said band being supported in proper position by a bar 53 secured thereto and to frame 45 23. An operating shaft 54 is extended through the two ends 51' of band 51, having threaded connection with one of said ends and having rotary connection with the other, said shaft being operated manually by a hand wheel 55 secured on one end thereof, whereby to press and retain said shoes against the brake drum and to release them therefrom. This manually adjusted brake means is adapted to be pre-set and thus functions as a secondary control means or to be used in conjunction with the above described primary control means, both of which are adapted to be pre-set or adjusted for accurately producing the desirable retarding effect and tension, under all normal conditions, so as to constantly maintain an even and uniform tension in the material.

In conjunction with said primary and secondary control means provided with this invention, I furthermore provide control means which is automatically actuated under abnormal conditions, as when the material breaks or when the pull on the material is suddenly considerably decreased. This automatic control means preferably comprises brake means which is applied to drum 50, as for example, a brake band 56 carrying brake shoes 57 which engage the interior of said drum, said band 56 being actuated by means of a block 58 cooperating with knuckles 59 provided on the adjacent ends of band 56. An operating lever 60 is secured with one end to said block 58 and has 70 75

its other end pivoted to a rod 61 which is pivotally connected with a lug 62 provided on the side of arm 20. A bar or rod 63 is secured to band 56 and extends therefrom to frame post 23 for supporting the band in its proper position.

With this arrangement, when the material is traveling under the usual conditions and is under normal tension, as indicated in Fig. 1 of the drawings, the guide roller 16 with its supporting arms 20 are forced rearwardly into their elevated operative position, and they in turn force rod 61 and lever 60 rearwardly into the brake-release position, as indicated in full lines in the drawings, thereby moving block 58 and shoes 57 also into the brake-release position, as best shown in Fig. 3. Then, whenever the material breaks, or when the pull on the material is decreased and the latter becomes slack, and the roll endeavors to unreel ahead of the lead, the arms 20 with the guide roll 16 carried thereby will, by the force of gravity, promptly descend into the idle position, while rod 26 is thereby freely drawn outwardly of dash-pot 24, as indicated by the broken lines in Fig. 2; thereby drawing lever 60 forward so as to expand brake band 56 and press brake shoes 57 firmly against the brake drum, and promptly checking and stopping the rotation of shaft 32 with its pulleys 31, and therewith also promptly checking and stopping belts 30 which travel with said pulleys and as a result promptly stopping the material roll 14 to prevent any further unreeling and slackening of the material.

It is apparent from the above disclosure that with my invention I have provided means for normally maintaining a slight tension in the material as it travels from the roll, and that at the same time the variation in the retarding effect required due to the change in the size of the roll, is automatically compensated for with this invention. It is also apparent that I have provided for readily applying additional retarding and tensioning stress to the material whenever that is needed, so that the retardation can be definitely adjusted to provide the exact tension desired; also that these two tension control means are accurately adjustable for providing a very elastic tension control for unreeling material to cover the various usual or normal conditions. It is furthermore evident that with my automatic control means I provide a prompt check and stop of the unreeling material whenever any unusual condition sets in, as when the material breaks or when the pull on the material is suddenly decreased or stopped, whereby any further unreeling of the material is automatically checked or stopped and the roll is prevented from running ahead of the lead. This invention thus provides a very elastic control means which covers an exceptionally wide range of tension control on sheet material traveling from a roll, and which can be very readily adjusted to produce from a very mild to a very strong retarding effect on the roll and tension in the material unreeling therefrom.

I claim:

1. Tension control means for material traveling from a roll, comprising belt means mounted to have an arced contact with the roll and to be driven thereby, rotary means for supporting said belt means, brake means adjustably applicable to one of said rotary means for retarding its movement and the movement of said belt means to a predetermined extent, for maintaining an even tension in the material, and other brake means connected to said adjustable brake

means for automatically stopping the travel of said belt means and roll upon tearing of the material.

2. Tension control means for material traveling from a roll, comprising means engaging the material on the roll and being driven thereby, means connected with said driven means for exerting a slight retarding effect thereby on the roll and the material, secondary means for causing additional retarding effect on said driven means, and automatically actuated means for placing additional retarding effect on the driven means and roll when the material suddenly slackens.

3. Means for controlling the tension in traveling material, comprising means which engages the material and is driven thereby, primary means for causing a slight retarding effect on said driven means and thereby on the material, means adjustable for causing additional retarding effect on said driven means, and means automatically actuated by the sudden variation of tension in the material for automatically controlling the movement of said driven means and thereby the travel of the material under abnormal conditions and for stopping the roll upon tearing of the material.

4. Tension control means for material traveling from a roll, comprising belt means and means for supporting it so as to engage the roll and to be driven thereby, means carried by some of said supporting means for producing a slight and automatically equalized retarding effect on the belt means and thereby on the roll, means operating on other of said supporting means to produce an additional and predetermined retarding effect upon said belt means and roll, guide means engaged by the traveling material and moved thereby while under normal tension, and automatic brake means actuated by said guide means to stop the travel of said belt means and the roll when the material breaks and when it suddenly slackens.

5. Tension control means for material drawn from a roll, comprising endless belt means and rotary means for supporting the same to produce an arced contact with the roll so as to be driven thereby, means carried by some of said rotary means for producing tension in and a slight retarding effect on the belt means and thereby on the roll, means operable on some of said rotary means to produce a certain retarding effect upon the belt means and roll under normal conditions, guide means over which said material travels and which normally moves against gravity to an elevated position, automatic brake means connected with the last mentioned rotary means, and means connecting said guide means with said automatic brake means to actuate the latter when the guide means descends under the action of gravity, upon any sudden slackening or breaking of the material.

6. Tension control means for material traveling from a roll, comprising belt means and means for supporting the same so as to engage the roll and to be driven thereby, means connected with some of said supporting means for normally producing a slight retarding effect on the belt means and the roll and tension in the material, guide means over which said material travels and which is normally carried to a retracted position thereby, automatic retarding means to act on said belt means, means connecting said automatic retarding means with said guide means and being normally held in release position thereby but being

5 moved to active position therewith when the material breaks or suddenly slackens, and check means connected with said guide means to provide for a slow retracting movement but a prompt 5 forward movement into active position thereof and of the automatic retarding means.

7. Tension control means for material drawn from a roll, comprising belt means and rotary means for supporting the same to produce an 10 arched contact with the roll and to be driven thereby, spring-pressed weight means operating on some of said rotary means for producing a slight and automatically equalized effect on the belt means and thereby on the roll, friction 15 brake means operating on another of said rotary supporting means to produce an additional retarding effect on said belt means and roll, means for manually adjusting said brake means, guide means engaged by the traveling material and during 20 normal operation moved thereby against gravity, automatic brake means mounted in combination with said friction brake means, and means for connecting said guide means with said automatic brake means to actuate the latter and 25 take up slack in the material upon any slackening thereof and for automatically stopping the roll upon tearing of the material.

8. Tension control means for material drawn from a roll, comprising belt means and rotary 30 means for supporting the same so as to engage the roll and to be driven thereby, adjustable weight means depending from some of said rotary means and thereby carried by said belt means for producing a slight retarding effect on 35 the roll and material, spring means connected with said weight means to compensate for the varying retarding effect thereof due to the varying size of the roll, drum means on some of said rotary means, manually adjustable brake means 40 on said drum means for retarding the rotation thereof and of said rotary means for producing a selected retarding effect thereon and on said belt means, automatic brake means connected with said drum means, guide means over which said 45 material travels and which it normally elevates, link means connecting said guide means and auto-

5 matic brake means for automatically actuating the latter when the material suddenly slackens and for automatically stopping said belt means and roll when the material breaks, and check means connected with the guide means to provide for a slow retarding movement but a prompt forward movement into active position thereof and of the automatic brake means.

9. Tension control means for material traveling from a roll, comprising endless means engaging the roll and driven thereby, rotary means for supporting said endless means, brake means adjustably applicable to the rotary means for retarding the movement of the endless means and the roll to a selected extent and maintain an even 15 tension in the material, and brake means operating automatically upon the rotary means to stop the same and the endless means and the roll upon sudden slackening or tearing of the material.

10. Tension control means for material traveling from a roll, comprising endless means and means for movably supporting the same to engage the roll and be driven thereby, means connected to said supporting means for normally retarding the movement of the endless means and the roll to a selected extent, and brake means normally inactive but operating automatically on 20 said supporting means for stopping the movement of the endless means and the roll upon sudden slackening or tearing of the material.

11. Tension control means for material traveling from a roll, comprising endless means engaging the roll and driven thereby, supporting means whereon said endless means travels, brake means connected to said supporting means and normally operative to retard the movement thereof and of the endless means and the roll to a selected extent, guide means whereon said material travels, and automatic brake means connected with 35 said guide means to operate on said supporting means, being normally inactive but becoming active for automatically stopping said endless means and the roll upon sudden slackening or 40 tearing of the material.

45 ARTHUR W. BROMS.
